UNITED STATES PATENT OFFICE

163,130

MEAT BASTING PERCOLATOR

James A. Malben, Jr., Kansas City, Mo.

Application April 11, 1949, Serial No. 1,903

Term of patent 3½ years

(Cl. D44—26)

To all whom it may concern:

Be it known that I, James A. Malben, Jr., a citizen of the United States, residing at Kansas City, in the county of Jackson, and State of Missouri, have invented a new, original, and ornamental Design for a Meat Basting Percolator, of which the following is a specification, reference being had to the accompanying drawing forming a part thereof.

Fig. 1 is a side elevational view of a meat basting percolator, showing my new design.

Fig. 2 is an end elevational view, and

Fig. 3 is a top plan view thereof.

I claim:

The ornamental design for a meat basting percolator, as shown.

JAMES A. MALBEN, JR.
